US0D1003389S

(12) **United States Design Patent** (10) **Patent No.:** **US D1,003,389 S**
(45) **Date of Patent:** **** Oct. 31, 2023**

(54) **IONIZER CONTROLLER MODULE**

(71) Applicant: **SMC CORPORATION**, Tokyo (JP)

(72) Inventor: **Akira Tadano**, Tsukubamirai (JP)

(73) Assignee: **SMC CORPORATION**, Tokyo (JP)

(**) Term: **15 Years**

(21) Appl. No.: **29/785,608**

(22) Filed: **May 26, 2021**

(30) **Foreign Application Priority Data**

Dec. 1, 2020 (JP) ..... 2020-025886 D

(51) **LOC (14) Cl.** **23-04**

(52) **U.S. Cl.**

USPC **D23/355**

(58) **Field of Classification Search**

(57) **CLAIM**

The ornamental design for an ionizer controller module, as shown and described.

DESCRIPTION

FIG. 1 is a front, top, and left side perspective view of an ionizer controller module showing the new design.

FIG. 2 is a front, bottom, and right side perspective view thereof.

FIG. 3 is a rear, top, and left side perspective view thereof.

FIG. 4 is a front elevational view thereof.

FIG. 5 is a rear elevational view thereof.

FIG. 6 is a top plan view thereof.

FIG. 7 is a bottom plan view thereof.

FIG. 8 is a left side elevational view thereof; and,

FIG. 9 is a right side elevational view thereof.

The broken lines depict portions of the ionizer controller module that form no part of the claimed design.

1 Claim, 9 Drawing Sheets
